UNITED STATES PATENT OFFICE.

NATHANIEL MINTZ AND CHARLES C. HIERS, OF ST. PAUL, MINNESOTA.

SAFETY DEVICE FOR CLOTHES-WRINGERS.

1,381,423.

Specification of Letters Patent. Patented June 14, 1921.

Application filed August 7, 1920. Serial No. 401,938.

To all whom it may concern:

Be it known that we, NATHANIEL MINTZ and CHARLES C. HIERS, citizens of the United States, residing at St. Paul, in the 5 county of Ramsey and State of Minnesota, have invented certain new and useful Improvements in Safety Devices for Clothes-Wringers, of which the following is a specification.

10 This invention relates to safety devices for clothes wringers, and more particularly to power driven wringers of the reversible type.

An object of our invention is to provide a 15 safety device of improved novel construction, whereby to increase the efficiency and extend the utility of devices of this character.

20 A further object of our invention, is the provision of a combined finger guard to prevent injury to the fingers, and scraper to prevent clothes from clinging to the rolls, commonly causing them to wind upon themselves.

25 Our invention contemplates the provision of a unitary device, which may be readily lifted off of one side of a reversible wringer, and attached to the other, the unitary device embodying a bodily movable clothes feeding 30 table, which automatically actuates a finger guard concurrently with its feeding movement to lift said guard out of the way, the feeding movement being imparted to the table by the hand by grasping it at a safe 35 point comparatively remote from the rolls.

To this end, the invention consists in the construction, combination and arrangement of parts hereinafter described and claimed. In the drawings forming part of this specification:

40 Figure 1 is a perspective view of a wringer embodying our invention.

Fig. 2 is a diagrammatic side view of the wringer rolls showing the invention in its 45 normal position.

Fig. 3 is a diagrammatic side view showing the table pushed partly forward.

Fig. 4 is an elevation of one of the side edges of the table.

50 Fig. 5 is a perspective view of one of the side frame members.

Fig. 6 is a vertical sectional view on line 6—6 of Fig. 1.

Fig. 7 is a fragmentary perspective view of the spring mechanism for the table. 55

Fig. 8 is a perspective view of one of the top supporting brackets.

Fig. 9 is a perspective view of one of the lower supporting brackets, and

Fig. 10 is a diagrammatic end view of the 60 rolls, showing the table in its foremost position.

In Fig. 1, A designates the main frame of a clothes wringer, and B and C the respective upper and lower horizontally disposed 65 rolls thereof rotatably supported in the frame, either of the shafts b and c of the rolls being customarily connected with mechanism (not shown) by which they may be driven. The usual gears D, positively 70 connect the two rolls in rotating relation, the usual adjustment screws E being provided whereby the distance between the axes of the rolls may be controlled.

Each of the upright members d of the 75 frame A, shown in the drawings, has smooth vertical faces 1, parallel to each other, the upright fitting snugly between the legs 2 of the U-shaped bracket 3, the latter having suitable screw holes 4 whereby it may be 80 firmly secured in position above the upper roll B. Extending at right angles to the faces of the uprights, on the legs 2, are the lugs 5, having vertically disposed pin holes 6.

85 Preferably aligned vertically with the lug 5, and firmly secured to the upright below the roll C, is the bracket 7, the lug 8 thereof having pin hole 9 similar to the pin hole 6.

Supported on the respective lugs of the 90 uprights is an auxiliary frame consisting of the side frame members F, each being formed with a pair of spaced outwardly extending lugs 11, spacedly registering with the lugs 5 and 8, so as to rest on the respective tops 95 thereof, each of said pair of lugs having a downwardly directed pin 6' to fit snugly into the pin holes of the lugs, so that said side members may be readily lifted bodily 100 out of engagement with the supporting lugs. Each of the side members is formed on its inner side with a groove or slideway 12, extending longitudinally outwardly and slightly downwardly, and an elongated horizontally disposed lug 13, having suitable 105 bolt holes 14, whereby the laterally extend-

ing horizontally disposed frame member 15 may be securely bolted thereto to hold the side members in fixed spaced relation. G designates the feed table, extending snugly 5 from one side member to the other and being slidably supported therebetween, by means of the tongues 16 extending laterally from the side edges of the table, and fitting slidably in the groove 12. When the edge 17 10 abuts against the forward wall 18 of the groove, the feeding or forward edge 19 of the table, will barely contact with the lower roll C, so that when a thin sheet of fabric is placed therebetween the moving rubber 15 covered rollers will grip the fabric. The spring 20, (which is preferably formed as shown) extends between the side frame members, and projects with its ends 21 through openings 22 in the webs of the side 20 members.

Centrally, the spring engages under constant stress, a pin 23, projecting from the underside of the table, whereby the latter is held in its normal rearmost position as 25 shown in Fig. 2 of the drawings.

As described in the foregoing, the groove 12 is inclined downwardly, whereby the table is supported in inclined position for the purpose of draining the surplus water.

30 Rotatably journaled at the outer edge of the table, and arranged in parallelism with the rolls of the wringer, is the idler roller 24, over which the clothes are drawn in the process of wringing. The roller also serves 35 as a convenient handle to be gripped by the hand to push the table forward and thereby bring the clothes into engagement with the rotating rolls.

As the receptacle containing the clothes to 40 be wrung is usually located just under the outstanding table, the clothes, in the process of wringing, must be pulled vertically out of the water and dragged abruptly forward over the edge of the table. By the use of 45 the roller 24, the movement of the clothes is facilitated, it not being necessary for the attendant to be constantly manipulating the clothes to help them over this abrupt turn.

In operation, an end of the garment is inserted from above downwardly through the 50 gap 25, which separates the feeding edge 19 from the wringer rolls, as shown in dotted lines in Fig. 2. The roller end of the table is now thrust forward, until the end of the 55 inserted garment engages with the rolls as shown in dotted lines in Fig. 3. The moving rolls will now grip the garment between them, and as the hand is removed, the spring 20 will return the table to normal position. 60 If the garment should stick to the surface of the table, the spring will yield and thereby permit the table to move before the garment is rent, the movement of the table constituting a signal to the attendant that assistance 65 is required.

Further, as the table is pushed forward, and the clothes begin to move through the wringer, the hand feels the movement of the roller, which is a signal that the rolls have gripped the inserted end.

To prevent accidental insertion of the fingers between the power driven rolls, we provide an automatically actuated finger guard H. The guard device comprises a shield member a, extending laterally from end to 70 end of the wringer rolls, said shield member having at each end a rearwardly extending arm 26, formed at its outer extremity with a finger piece 27, whereby the guard may be raised by hand. The arms extend along side 75 the respective side members F, and are pivoted, intermediate their ends by means of the pivots 28, on said side members, said pivots forming a fulcrum whereby, when either 80 finger piece is depressed, the shield may be 85 raised above the surface of the table, to clear any unusually thick mass of folds that might form on the table adjacent the shield. The upper edge of the shield has a blunt 90 knife edge 29, which is normally preferably 90 slightly spaced from the surface of the upper roll B, so that when thin light fabrics cling to the latter said knife edge will engage it and peel it off.

On the under side of each of the arms 26, 95 is a cam 30, co-operating with a cam surface 31 on the table G, the cam being suitably curved so as to hold the shield in its normal position when the table is in its normal position (Fig. 2).

The lower portion of the shield is formed with a curve concentric with the pivots 28, its lower edge extending normally a distance below the top of the table, and being formed with upwardly diverging surfaces 32, to 105 form oppositely directed inclined faces to facilitate the passing of the clothes in both directions, it being sometimes necessary to reverse the feed. These bevels are especially useful, in that passing buttons engage them and are thereby crowded downwardly edge foremost, thus avoiding breaking of same. When the shield is in normal position, the fingers cannot touch the rolls in the act of inserting clothes in the gap 25, as shown in 115 Fig. 2. After insertion is completed the table is pushed forward, as hereinbefore explained, the cam face 31 engaging the cam 30, thereby automatically raising the shield. The device may be bodily lifted from the 120 lugs 5 and 8 on one side of the frame, and hung on those of the other. While we have shown our invention applied to a clothes wringer, it is to be understood that it may be used as a safety device at the feeding 125 position of other machines.

We claim:

1. In a device of the class described, the combination with a clothes wringer frame and parallel horizontally disposed wringer 130

- rolls contactingly mounted one above the other thereon, of a frame extending outwardly from the side of the wringer frame, an upwardly swingable finger shield in 5 front of said rolls, a table in front of said shield the forward edge thereof parallel with said rolls and normally spaced therefrom and from said shield, said table being mounted to slide on said extending frame 10 under said shield to raise it and toward a point midway between said rolls to bring said forward edge to a position adjacent the point of contact between said rolls for the purpose set forth.
- 15 2. In a device of the class described, the combination with a main frame and parallel horizontally disposed rotatable rolls supported one above the other thereon and arranged to peripherally contact with one another, of an auxiliary frame extending outwardly from the side of said main frame, a table slidably mounted on said auxiliary frame and normally spaced from said rolls and slidable to a position in close proximity 20 to said rolls, means tending constantly to hold said table in normal position, a movably mounted finger guard in front of the line of contact of said rolls, a part thereof normally extending into the path of travel 25 of said table, and means on the table for pushing said guard out of said path of travel when the table is moved.
3. The combination of a clothes wringer of the class described, similar outstanding 35 supporting lugs on opposite sides thereof, and safety mechanism movable as a unit having extensions loosely interlocking with the lugs of either side of said wringer, said safety mechanism comprising a frame, a 40 table slidably mounted on the frame so as to be slid against one of the wringer rolls and normally spaced from the latter, and an upwardly swingable hand operable finger guard in front of the wringer rolls in the 45 path of travel of said table.
4. A clothes wringer comprising a main frame, a pair of horizontally disposed wringer rolls rotatably mounted in contacting relation one above the other on the frame, safety guard mechanism extending 50 from the side of the frame, comprising an auxiliary frame supported on the side of the main frame, an upwardly movable finger guard movably mounted on the auxiliary
- frame and located in front of the rolls, a 55 clothes carrying table slidably supported on the auxiliary frame and spaced from said finger guard and movable bodily toward the lower of said rolls so as to press the clothes thereagainst, said table engaging in its travel 60 with said guard to gradually raise the latter as the table is moved, and a roller rotatably mounted at the outer edge of said table, said roller arranged in parallelism with said wringer rolls. 65
5. In a device of the class described the combination with a clothes wringer frame and horizontally disposed wringer rolls rotatably mounted in contacting relation one above the other on the frame, of safety 70 guard mechanism extending from the side of the frame, comprising a frame supported at opposite sides of the wringer frame, a finger guard disposed edgewise in front of the rolls and extending laterally the length 75 thereof, said guard having movable connection with the frame to render it upwardly movable, and a slidable clothes supporting member slidably supported on the frame to slide transversely of the rolls to push the 80 clothes against one of the latter, said member being formed with an inclined face engaging said guard to raise the latter in the initial portion of its sliding movement.
6. In a device of the class described, the 85 combination with a clothes wringer frame and horizontally disposed wringer rolls contactingly and rotatably supported one directly above the other on said frame, of finger guard mechanism bodily movable as a 90 unit, comprising a frame which fits over the front of the wringer frame, a table normally spaced from the rolls and slidably edgewise on the frame to a position midway between said rolls so as to engage with its edge the 95 lower roll, an upwardly movable finger guard for the rolls movably mounted on the frame and normally positioned in the path of said table and operatively connected with the latter to be actuated thereby responsive 100 to the sliding movement thereof, and readily separable connections between the wringer frame and said unit for the purpose set forth.

In testimony whereof we affix our signatures.

NATHANIEL MINTZ.
